US0D1001796S

(12) **United States Design Patent** (10) **Patent No.:** **US D1,001,796 S**
(45) **Date of Patent:** **** Oct. 17, 2023**

(54) **LAPTOP COMPUTER**

(71) Applicant: **Quanta Computer Inc.**, Taoyuan (TW)

(72) Inventors: **Wen-Hung Tsai**, Taoyuan (TW);
Gwo-Chyuan Chen, Taoyuan (TW);
Chi-Jen Yu, Taoyuan (TW); **I-Chi Chen**, Taoyuan (TW)

(73) Assignee: **QUANTA COMPUTER INC.**, Taoyuan (TW)

(**) Term: **15 Years**

(21) Appl. No.: **29/722,231**

(22) Filed: **Jan. 28, 2020**

(30) **Foreign Application Priority Data**

Oct. 16, 2019 (TW) 108306412

(51) **LOC (14) Cl.** **14-02**

(57) **CLAIM**

The ornamental design for a laptop computer, as shown and described.

DESCRIPTION

FIG 1 is a top, front and left perspective view of a laptop computer in an unfolded state, showing our new design; FIG. 2 is a front view thereof; FIG. 3 is a rear view thereof; FIG. 4 is a left side view thereof; FIG. 5 is a right side view thereof; FIG. 6 is a top plan view thereof; FIG. 7 is a bottom plan view thereof; FIG. 8 is a top, rear and right perspective view thereof; FIG. 9 is a top, front and left perspective view of the laptop computer with the screen of the laptop computer overlaying the keyboard; and, FIG. 10 is a top, front and left perspective view of the laptop computer in a folded state, wherein the screen of the laptop computer is folded so that the keyboard sandwiched between the two portions of the screen.

1 Claim, 10 Drawing Sheets
